WORK SUPPORTING AND GUIDING DEVICE
FOR SHOE SEWING MACHINESLillian P. Simmons and Frank J. Connova,
Chicago, Ill.

Application October 2, 1948, Serial No. 52,544

6 Claims. (Cl. 112—62)

1

This invention relates to improved shoe sewing mechanisms by which the individual parts of shoes are secured together prior to lasting. More particularly, the invention is directed to an improved work supporting and welt-guiding plate utilized in connection with a shoe sewing machine, which facilitates the operation of inserting a line of stitching simultaneously through an unattached welt strip, insole and pre-formed upper members to secure said members together.

Pre-welted shoes made by securing a welt to the margin of the upper member prior to lasting are known in the art. Further, it has heretofore been suggested that a pre-welted shoe having desirable characteristics could be formed by attaching an insole to a unitary member formed of the welt and upper prior to lasting the shoe.

Illustrative of such pre-welted shoes is the disclosure of British Patent No. 405,625, dated February 2, 1934, which describes a method of making pre-welted shoes, wherein the welt and upper members are initially secured together to form a unitary member. The individual parts of the unitary member are first temporarily fastened by the use of tacks preparatory to inserting preliminary tacking stitches. After the welt and upper are formed into the unitary member with the aid of tacks, the insole is sewn to the welt-upper unit by a line of securing stitches. Thus, by the method set forth in the British patent, fitting and tacking operations are necessitated in forming the unitary welt-upper member and an additional securing operation is required to attach the insole to the previously formed unitary member. In view of the number of steps involved, including the preliminary securing steps, the cost of manufacture of shoes made in accordance with the disclosure of the aforesaid patent is inherently high, and accordingly, the process has not achieved commercial success.

It is, therefore, an object of this invention to provide a novel work supporting plate for use in making pre-welted shoes by uniting separate and unattached welt, upper and insole pieces during a single sewing operation prior to the lasting of the shoe parts.

Another object of the invention is to provide an improved work supporting and welt-guiding plate whereby separate and unattached welt, upper and insole members may be united by a line of stitching formed during a single sewing operation while the shoe parts are maintained in an inverted position with the marginal edges thereof in alignment.

Another object of the invention is to provide

2

an improved device for forming pre-welted shoes by (1) superposing the corresponding portions of an unattached preformed upper member and an unattached preformed insole having the edges thereof in alignment with the edge of a welt strip section, and (2) inserting a line of securing stitches a spaced distance from the edges thereof around the preformed members and through the shoe components while maintaining the marginal edges thereof in alignment.

A further object of the invention is to provide an improved sewing mechanism which will facilitate the maintenance of marginal edges of superposed unattached shoe parts such as the welt, upper member and insole, in alignment during the insertion of a line of stitching about the periphery of the shoe unit a spaced distance from the edge thereof.

It is a further object of the invention to provide an improved work supporting plate for a shoe sewing machine, which is provided with a non-confining guide groove for the welt strip, together with supporting means for the inner sole and upper member when positioned with the edges thereof in superposed relation beneath the presser foot of the sewing device.

Another object of the invention is to provide an improved work supporting plate for a sewing machine, which is provided with a slot, through which the welt strip is freely fed to the sewing area beneath the presser foot from beneath the work supporting plate.

A further object of the invention is to provide an improved work supporting plate for a sewing machine, whereby the welt strip is guided to the sewing area, but which does not confine the movement of the welt strip and the shoe parts united thereto after leaving the sewing area.

A still further object of the invention is to provide a unitary work supporting and welt-guiding plate for use with a sewing machine, which plate comprises a member having a relatively flat upper surface and an elongated needle aperture positioned between spaced and opposed abutments that form a welt groove with the height of each of the abutments progressively increasing from a position adjacent the central portion of the elongated needle aperture in a direction toward the infeeding end of the welt groove.

The invention also resides in certain novel structural characteristics of the improved work supporting and welt-guiding device for sewing mechanism, which facilitate the carrying out of the foregoing objects and which contribute both to the versatility of performance and to its ease

of operation, as well as to its dependability and efficiency.

Other objects and advantages of the invention will become apparent from the following detailed description taken in connection with the accompanying drawings, in which:

Fig. 1 is a perspective view of portions of the head of a sewing machine, showing a shoe welt, insole and upper member in superposed relation and having the edges thereof aligned and positioned beneath the raised presser foot of the sewing machine;

Fig. 2 is a perspective view of an improved work-supporting plate for a shoe sewing machine, wherein is provided a welt slot, through which a welt strip passes, a needle aperture, and also a channel or groove for the welt strip which serves as a non-confining guide means;

Fig. 3 is a cross-section taken on line 3—3 of Fig. 2;

Fig. 4 is a cross-section taken on line 4—4 of Fig. 2, except the presser foot has been shown in lowered position;

Fig. 5 is a plan view of the improved work supporting plate;

Fig. 6 is a side elevation of the work supporting plate;

Fig. 7 is a bottom view of the work supporting plate;

Fig. 8 is an elevation of the right side of the improved work supporting plate shown in Fig. 5;

Fig. 9 is an elevation of the left side of the work supporting plate shown in Fig. 5;

Fig. 10 is an enlarged section of the work supporting plate taken on line 3—3 of Fig. 1;

Fig. 11 is an enlarged plan view of the reduced neck portion showing the welt groove and slot of the work supporting plate;

Fig. 12 is a perspective view of a welt, insole and upper member provided with an open toe and heel, which have been secured by a line of stitching;

Fig. 13 is a bottom view of the shoe component shown in Fig. 12;

Fig. 14 is a perspective view of a shoe component formed of a welt, insole and upper member provided with closed heel and toe portions;

Fig. 15 is a bottom view of the shoe component shown in Fig. 14;

Fig. 16 is an exploded view disclosing the shoe components in Fig. 12, with a last inserted therein, and indicating the assembly of a heel seat, filler and shank;

Fig. 17 is a cross-sectional view of the assembled shoe indicated in Fig. 16 taken through the heel section; and

Fig. 18 is a cross-sectional view of the assembled shoe indicated in Fig. 16 taken across the forward portion of the shoe, to which an outer sole has been secured.

While this invention is susceptible of various modifications and constructions, we have shown in the drawings and will here describe in detail the preferred embodiment. It is to be understood that we do not intend to limit the invention by such disclosure and we aim to cover all modifications and alternative construction and steps falling within the scope and spirit of the invention as defined in the appended claims.

In forming shoes by our improved method, a separate and unattached preformed upper member 10 is positioned above a welt strip 12 with the edges of the separate preformed upper member 10 and welt strip 12 in alignment. Preferably the inside heel breast marginal portion of the pre-

formed upper is initially superposed relative to a portion of the welt strip adjacent to its extremity. Inasmuch as the ends of the welt strip are overlapped during a subsequent sewing operation, the end of the welt strip in contact with the separate preformed upper may be skived or feathered, as shown by reference numeral 11, prior to the above positioning operation, although, if desirable, this step may be carried on subsequent to the sewing operation.

The preformed upper member 10 and welt strip 12 are arranged with the finished or outside of the welt in contact with and underlaying the finished or outside of the preformed upper member. By the term "preformed upper member" we mean to define the shoe upper pieces which are conventionally made up in a fitting room. Such upper members are cut to a desired configuration, depending upon the style and size of the shoe being made, and may be provided with a stitched edging 14, counter 16, lining 18, open toe and open heel portions, 20 and 22, respectively, heel stay 24, box toe 15, vamp and other features normally employed in shoe structure. The material from which the preformed upper member 10 is formed may be leather, textile, plastic, or other web material conventionally employed, and the surface which forms the exterior of the shoe may be plain or decorated in any suitable manner.

A preformed insole member 26 is laid over the superposed preformed upper member 10 and welt strip 12 with the marginal edge of the insole at the inside heel breast positioned in corresponding relation to the inner heel breast position of the upper member 10. The preformed insole 26 is positioned on the upper member 10 with the corresponding edges in alignment and with the finished side, i. e., the inside, in contact with the unfinished side of the upper member. The insole member 26 is preferably formed of soft flexible leather, although other flexible web materials, such as textiles and the like, may be employed. By arranging the separate and unattached shoe pieces 10, 12 and 26 in the manner described, an assembly is provided, as shown in Fig. 1, wherein the corresponding marginal edges of the insole 26 and upper member 10 are in register and superposed relative to a portion of the welt strip 12 adjacent to the end thereof with the edges of the welt strip in alignment with the edges of the insole and upper member.

The separate and unattached shoe pieces 10, 12 and 26 after having been assembled in the above defined manner are secured together to form a unitary shoe component by a line of stitching 27 passing through the welt strip a spaced distance from the outside edge thereof and through the preformed insole 26 and preformed upper member 10. The line of stitching does not necessarily pass through all of the pieces, as the line is inserted about the marginal edges of the shoe unit, since certain portions of the insole and upper member may be left free of stitching depending upon the style and type of shoe being constructed, as will be later explained.

It will be apparent that the insertion of a line of stitches through and a spaced distance from the edges of the welt strip 12 and other pieces to be united presents a difficult task for even a skillful operator, since the separate members must be fed in superposed position with the edges thereof aligned to the sewing area where the stitches are inserted. The maintenance of the separate and unattached pieces in superposed

relation with the edges thereof in alignment is complicated by the fact that the line of stitching follows a path of reverse curvature and the degree of curvature changes in accordance with the location of the shoe portions being united. The curvature is greatest at the heel and toe portions of the shoe unit where the greatest difficulty is encountered in properly maintaining the superposed and unattached pieces in aligned position as the assembly of pieces passes into the sewing area.

In order to make possible the rapid insertion of the stitches through the unattached pieces to be secured by relatively unskilled operators and with a minimum of rejected shoe units, we have provided an improved sewing mechanism which serves to guide the welt strip into a selected position beneath the presser foot in the sewing area of the improved mechanism. Thus, by employing our improved sewing means to position the welt strip continuously relative to the line of stitches as they are inserted, the operator's attention can be directed to maintaining the upper member 10 and insole 26 in juxtaposition with the edges thereof in alignment with each other and with the edge of the welt strip 12.

The improved sewing mechanism which is shown in Figs. 1 to 11, inclusive, comprises a unitary work supporting plate 50 which serves both as a supporting means for the shoe pieces while the stitches are being inserted therethrough and as a means for guiding the welt strip 12 to, but not confining said strip in, a predetermined position within the sewing area. The work supporting plate 50 is shown in Figs. 1, 3 and 4 attached to a conventional sewing device which is adapted for sewing a welt strip to an unlasted upper member. By way of example, the mechanism of a Puritan shoe machine has been employed to illustrate the type of sewing device which may be utilized, although other types of sewing devices may be used. The stitch-forming mechanism of the sewing machine comprises an awl 52 which is reciprocated by shaft 54 in which it is mounted, a needle threading looper 56, and a reciprocating hooked straight-shank needle 58, which, together with the needle castoff (not shown), are actuated in proper timed relation by connections to conventional sewing machine elements which form no part of the present invention.

Reference numeral 60 indicates a presser foot, which, when moved into its lowered position, as best shown in Fig. 4, is biased by spring means (not shown) to compress the shoe pieces between the bottom of the foot and the work supporting plate 50 in the sewing area or zone. The platen 62 of presser foot 60 is formed relatively narrow in order to facilitate sewing closely adjacent to the aligned edges of the superposed welt strip 12, upper member 10 and insole 26. By sewing relatively close to the edges of the superposed shoe parts, labor and material are saved, since the need for trimming is eliminated. The type of presser foot conventionally employed to sew shoe vamps has been found suitable for this purpose, and the platen surface, i. e., the presser foot bottom, of such a vamping foot in contact with the material is approximately 0.625 of an inch long and 0.3125 of an inch wide with an elongated needle aperture positioned centrally between the sides thereof. Thus, with the platen side aligned with the edges of the shoe material, the center of the line of stitches through the shoe pieces will be inserted approxi-

mately 0.156 of an inch from the aligned edge of the shoe pieces.

The unitary work supporting plate 50 is of general rectangular shape, having a substantially flat upper body surface 51 and one end thereof formed with a reduced neck portion 64. The plate 50 is securely supported in a substantially horizontal position on a vertical standard 66 by the use of longitudinally extending dovetailed grooves 68 and 70 located on the bottom thereof of which coat with cooperating surfaces formed on the upper inside portions of walls 72 and 74 of standard 66. A bolt 76 having the shank end thereof threaded extends through aperture 78 of wall 74 and is secured in thread-equipped aperture 80 of wall 72. Rotation of bolt 76 serves to tighten the coating surfaces of walls 72 and 74 against the surfaces of the dovetailed grooves 68 and 70 to maintain the unitary supporting plate 50 in place.

The reduced neck portion 64 of the unitary work supporting plate 50 is provided with a welt groove 82 extending transversely of the reduced end portion 64 which is formed by a wall or abutment 84 and an oppositely opposed shortened wall or abutment 86 formed by narrow ridge 88 which is located adjacent to the outer end of the reduced portion 64. The top surface of ridge 88 is flattened and is located in substantially the same plane as the upper body surface 51 of the work supporting plate 50. A welt slot 90 is positioned adjacent to the leading edge 92 of welt groove 82 and is formed by extensions 94 and 96 of abutments 84 and 86, respectively, and by bridge member 98 which extends between ridge 88 and the body portion of plate 50. The walls or abutments 84 and 86 are spaced a distance apart slightly greater than the width of the welt strip to be sewn and the opening between the under surface of bridge member 98 and leading edge 92 is considerably greater than the thickness of the welt strip 12 in order that the strip may freely pass through the slot 90 and slide in the groove 82 without binding.

As is shown in Figs. 2, 3, 5, 10 and 11, the leading edge 92 of the bottom of welt groove 82 is rounded at 100 and the groove progressively decreases in depth to the central portion 105 of needle aperture 106, at which point the height of the abutment 84 remains constant over the rearward portion thereof. Conversely, each of the abutments 84 and 86 progressively increase in height from the central portion of the needle aperture to the in-feed end of the welt groove. The rearward portion of the welt groove 82 is relatively shallow for purposes to be explained later and by way of illustration good results have been obtained under commercial operating conditions by employing a groove depth from the central portion of the needle aperture rearwardly of approximately one eighth the thickness of the welt strip.

As best shown in Figs. 1, 8 and 10, the leading part 104 of the reduced neck portion 64 extends downwardly below the plane of the remaining part of the reduced portion to form with the overhanging section 99 of bridge member 98 an opening 97 for welt slot 90 of considerably greater depth than that of the welt strip. The upper and lower surfaces of the bridge member 98 are substantially parallel and are positioned in acute angular relationship with the upper surface 51 of the work support plate 50, as is shown in Figs. 3 and 10. The material passing above the slot 90 is readily directed into the sewing area of the

sewing device by the slanted upper surface of bridge member 98 and the lower surface of the bridge member 98 cooperating with rounded leading edge 92 serves as a guiding means for directing the incoming welt strip into the welt groove 82.

The bottom of welt groove 82 is provided with an elongated needle aperture 106, the longitudinal axis of which is spaced from abutment 84 by a distance corresponding to the space between the aligned edges of the material and the line of stitches. As best shown in Figs. 5 and 10, the needle aperture 106 is preferably located closer to the abutment 84 than it is to abutment 86. The elongated needle aperture 106 is provided with an infeed end 107 and an outfeed end indicated by reference numeral 108. Ridge 88 extends from bridge member 98 along welt groove 82 to a position opposite a location substantially intermediate the central portion 105 and outfeed end 108 of needle aperture 106 where it preferably abruptly tapers to the level of the after portion of the welt groove bottom. The after portion 102 of the welt groove 82 is gradually rounded to present a surface from which the sewn material may freely pass without being impeded by friction.

Prior to superposing and aligning the edges of the separate welt strip 12, upper member 10 and insole 26 as described above, the end of the welt strip feeding from a welt supply (not shown) positioned below the sewing mechanism is passed through welt slot 90 over leading edge 92 of the groove 82 with the finished side facing in an upward direction. After aligning the edges of the superposed shoe pieces at the inner heel breast position, as above described, the presser foot 60 is released to compress the pieces beneath the platen 62, as shown in Fig. 4, within the sewing area.

The manner of uniting the shoe pieces by stitching is dependent upon the type and style of shoe being constructed. Figs. 12, 13 and 16 illustrate the continuous line of stitching inserted through the parts of an open toe and heel shoe. In the preforming of the upper member 10 for such a shoe, it is conventional to remove material from the inside tip position 28 across the toe to the outside tip position 30 and from the inside heel breast position 32 around the heel to the outside heel breast position 34. Thus, in sewing the shoe pieces of an open toe and heel shoe, the operator inserts a line of stitching extending forwardly from the inner heel breast position 32, through the marginal edges of the superposed welt strip 12, upper member 10 and insole 26 to the inside tip position 28. The line of stitching then is continued around the curvature of the toe through only the welt strip 12 and insole 26 to the outside tip position 30. From this point the line of stitching continues through the welt strip, upper member and insole until the outside heel breast position 34 is reached. The line of stitching then continues from the outside heel breast position 34 around the curvature of the heel to the inside heel breast position 32 passing through only the welt strip and insole member.

When the insole members designed for use in closed toe and heel shoes are preformed, a plurality of niches are placed therein, as is shown by Fig. 15. Reference numeral 36 indicates the inside tip niche and 38, 40 and 42 indicate the outside tip niche, inside heel breast niche and outside heel breast niches, respectively. In uniting the separate welt strip 12, upper member 10

and insole 26 to form a closed heel and toe shoe, as shown in Figs. 14 and 15, the line of stitches 27 is started, as previously described, at the inner heel breast position marked by the niche 40 and extends forwardly to the inside tip niche 36 passing through the welt strip, upper member and insole. The stitching continues from niche 36 around the curvature of the toe to outside tip niche 38 passing through only the welt strip and upper. From the outside tip niche 38, the stitching 27 continues to the outside heel breast niche 42 passing through the welt strip, upper and insole members. Between the outside heel breast niche 42 and the inside heel breast niche 40, the line of stitching rounds the heel portion and passes through only the welt strip 12 and the upper member 10.

From this description it will be evident that the insole is left free from the upper member and welt strip around the toe curvature from the inside tip niche 36 to the outside tip niche 38 and around the heel curvature from the outside heel breast niche 42 to the inside heel breast niche 40. Prior to completing the continuous line of stitches at the inside heel breast position, the welt strip is severed and overlaps the opposite end. The severed end thereof is skived to reduce the bulk of the overlapping portions of the welt strip.

During the sewing operation the shoe parts are inverted with the bottom side of the insole uppermost. Consequently, it will be noted that the operator can see only the edge of the welt strip with which the edges of the other shoe pieces are aligned during the insertion of the stitches. The welt strip feeding through slot 90 from beneath the work support plate 50 into welt groove 82 is positioned by abutments 84 and 86 which form the sides thereof. During insertion of the line of stitches in the sewing area which progressively moves about the contour of the shoe, the marginal edges of the upper member 10 and insole 26 to be sewn are maintained in superposed relation to the welt strip with the edges thereof in alignment. Since the line of stitches passes about reverse curves and also around the more abrupt curves of the heel and toe portions, it is necessary for the sewn portions leaving the sewing area beneath the platen 62 to move laterally either to the right or left, depending upon the specific portion of the shoe contour being sewed. By employing a shortened ridge 88, and providing a welt groove which progressively decreases in depth from the leading edge thereof rearwardly to the central portion 105 of the needle aperture and then remains constant over the rearward portion thereof to the rounded edge 102, as described above, the welt strip after being sewn to the other shoe pieces will freely ride over the rearward portion of abutment 84 or pass over or around the end 89 of ridge 88, thus facilitating the insertion of the line of stitching around the shoe parts. From the above discussion it will be evident that the welt slot and groove of the unitary work supporting plate 50 serve to guide the welt strip from a supply roll beneath the sewing machine to the proper location within the sewing area, but does not serve to confine the welt strip and the shoe pieces united therewith after they leave the sewing area. In view of the guiding, supporting but not confining action applied to the welt strip, an operator can readily follow the contour of the superposed shoe parts and insert a line of stitching a spaced distance from the edges there-

of through the marginal edges of the separate and unattached pieces.

After the welt strip, upper member and insole are sewed together, the shoe is lasted by inserting a last 44 into the interior of the sewn piece. The outer edge of the welt strip is pulled up which causes the lip 46, in the sewn edges of the welt strip, upper member and insole, to fold inwardly, as shown in Figs. 17 and 18, forming a well or recessed portion 49 across the bottom of the insole. A heel seat 41 is positioned in the heel portion of the recess and a filler 48 is then inserted having a thickness substantially equal to the greatest depth of the recessed portion 49. The filler may be preformed, as indicated in Fig. 16, and comprise a resilient material, such as compacted and cemented cork granules or other resilient and flexible material. Alternatively, the filler may be cast in the recessed portion 49 by spreading therein a semi-flowable mixture of paste-like materials conventionally used for the purpose.

After the filler 48 has been inserted, a shank 53 is placed across the instep of the shoe, as indicated in Fig. 16. The outsole 55 is then applied to the shoe bottom and secured to the unfinished side of the welt 12 by a line of stitching 57 inserted around the shoe welt a spaced distance from the edge thereof. The shoe heel is then applied, the parts trimmed and the shoe finished in any suitable manner known to the art.

We claim:

1. A unitary work supporting and welt-guiding plate for use on a shoe sewing machine comprising a member provided with a relatively flat upper surface having an elongated needle aperture provided with infeed and outfeed ends extending through said member, a first abutment positioned on one side of said needle aperture extending in a direction transverse of said plate, a second abutment positioned in opposed relation to said first abutment located on the opposite side of said needle aperture, said second abutment extending in spaced relation to said first abutment and terminating opposite to a position intermediate the central portion and the outfeed end of said elongated needle aperture, the heights of each of said opposed abutments being substantially the same and progressively increasing in one direction from the central portion of said elongated needle aperture to the extremities thereof, and the height of said first abutment being substantially constant throughout its length in the opposite direction from said central portion of the elongated needle aperture.

2. A unitary work supporting plate for use on a shoe sewing machine comprising a member provided with a relatively flat upper surface having an elongated needle aperture provided with infeed and outfeed ends extending through said

member, a first abutment positioned on the upper surface of said member located in spaced relation to the longitudinal axis of said elongated needle aperture, a second abutment oppositely disposed with respect to said first abutment extending in spaced relation thereto on the opposite side of said elongated needle aperture, said first and second abutments defining a welt groove having an in-feeding portion provided with a leading edge at the bottom of said groove, said second abutment terminating opposite to a position intermediate the central portion and the outfeed end of said elongated needle aperture, each of said opposed abutments progressively increasing in height from a position adjacent the central portion of said elongated needle aperture in a direction toward the leading edge of said welt groove, and the height of said second abutment being substantially constant throughout its length from a point opposite the central portion of said elongated needle aperture in the opposite direction.

3. A unitary work supporting plate as defined in claim 2 having the leading edge of the welt groove formed with a curved surface.

4. A unitary work supporting plate as defined in claim 2 provided with a bridging member extending intermediate the upper portion of said opposed abutments adjacent to the extremities thereof which defines with said leading edge a welt slot.

5. A unitary work supporting plate as defined in claim 2 having a welt slot located adjacent the in-feeding portion of the welt groove formed by extensions of said first and second abutments, said leading edge and a bridging member connecting the upper portions of said abutments.

6. A unitary work supporting plate as defined in claim 2 wherein the end of the second abutment located opposite said elongated needle aperture is provided with a downwardly extending taper.
